R. L. LOWMAN.
TRACER FOR PROJECTILES.
APPLICATION FILED APR. 19, 1918.

Patented July 22, 1919.

UNITED STATES PATENT OFFICE.

ROY LEIGHTON LOWMAN, OF WASHINGTON, DISTRICT OF COLUMBIA, ASSIGNOR TO
HARRY C. DODGE, OF BOSTON, MASSACHUSETTS.

TRACER FOR PROJECTILES.

1,310,708.

Specification of Letters Patent. Patented July 22, 1919.

Application filed April 19, 1918. Serial No. 229,599.

To all whom it may concern:

Be it known that I, ROY LEIGHTON LOWMAN, a citizen of the United States, residing at Washington, District of Columbia, have invented and discovered certain new and useful Improvements in Tracers for Projectiles, of which the following is a specification.

My said invention relates to improvements in tracers for projectiles and has for its object the ignition of the tracer composition by utilizing the inertia of a movable part in conjunction with a part fixed in the projectile. The force available due to this inertia is dependent upon the acceleration imparted to the projectile upon discharge from the gun. The force employed is commonly referred to as "set-back".

Referring to the accompanying drawings which are made a part hereof and on which similar reference characters indicate similar parts,

Figure 1 is a view of a projectile, of an accepted type, provided with a tracer of my improved construction.

Fig. 2, a longitudinal section through the tracer attachment showing the construction in detail, and

Fig. 3 a detail plan view of the disk 17. In said drawings the portions marked A represent the shell of the projectile and B the casing of the tracer. The body or casing B of the tracer is formed screw-threaded at a point 10 near its outer end and is adapted to be inserted through a screw-threaded aperture in the base of the projectile A and be attached thereto by engagement between said screw-threaded portion and the threads of said aperture. It has a head 11, the front corner of which is adapted to abut against an annular shoulder near the outer end of the aperture in the base of the shell, as clearly shown in Fig. 1.

Said casing B is formed with a central bore extending from its rear to a point near its inner end and has a tubular shell 12 mounted therein containing the tracer composition 13. A cap holder 14 is mounted in the outer end of said tube 12 having a socket to contain a cap 15 and formed with a central aperture 16 communicating with the chamber containing the tracer composition. A disk 17 preferably formed slotted and with a central hole, as shown in Fig. 3, covers the outer end of the cap holder and

its edges are adapted to rest on an annular shoulder in the casing B at point 18. A combined plug and firing pin 19 is mounted outside said disk, formed with a central projection 20, constituting the firing pin proper, and with an annular rim extending beyond said projection adapted to rest against the outer edge of the disk 17. A sealing device 21, consisting of a cup-shaped disk, is mounted in the outer end of the bore 65 of the body B and formed of compressible material and with a disk 22 of relatively soft compressible material between the same and the end of the firing pin.

The operation is as follows: Upon the discharge of the projectile from the gun the pressure upon the sealing device 21 serves to seal the joint around the outer edge of the plug 19 and prevent gases from passing into the chamber containing the other parts 70 of the device. The combination plug and firing pin 19 bears upon the shoulder 18 and prevents pressure from the gun chamber crushing the gas sealing device and the pressure against these parts holds the disk 80 17 in place. The cap holder 14 with the cap 15, the tube 12 and the tracer composition 13 are only held from moving rearwardly by the resistance of said disk 17. Upon discharge the acceleration of the shell is 85 so great that the inertia of the tube 12, tracer composition 13, and connected parts is so great that it overcomes the resistance offered by said disk 17 breaks through the same forces the rear end of the cap holder through 90 said disk, brings the cap F against the firing pin 20 and causes the cap to explode. The resistance offered by disk 17 is determined by the extent and number of slots and size of central hole, as well as by the material of 95 which it is composed, as will be readily understood. The fire from the explosion passes through the perforation 16 into the tube B and ignites the tracer composition 13. As soon as the projectile leaves the gun 100 and the pressure on the base of the tracer is relieved the gas generated by the burning of the tracer composition forces the cap holder 14, plug 19 and connected parts to the rear and expels them from the casing B. 105 The same pressure at the same time causes the tube 12 with the tracer composition to move forward in the casing B to the limit permitted by the perforation or chamber therein. This movement is aided by the re- 110

tardation of the shell on account of the air resistance. When the parts behind the tracer composition are expelled from the casing, the flame from such composition is 5 visible in the rear of the projectile and enables one to follow its flight.

It will be understood of course that modifications in the details of construction may be made without departing from the spirit 10 of my invention as defined in the following claims.

Having thus fully described my said invention what I claim as new and desire to secure by Letters Patent, is:

- 15 1. A shell provided with a tracer attachment comprising a body or casing, a movable member in said casing containing the tracer composition and having a cap holder on its outer end, a firing pin positioned on 20 a plug held in a fixed position in the outer end of said casing, and a fragile resistance device between the firing pin and the cap holder, substantially as set forth.
- 25 2. A projectile provided with a tracer attachment consisting of a shell fixed in its rear end, a sliding member mounted in said shell containing a tracer burning composition, a cap holder separably carried in the rear end of said sliding member, a firing pin 30 positioned in the rear end of the bore of said shell and a fragile resistance device mounted between said cap holder and said firing pin, said cap holder being formed with a communication leading into the chamber containing 35 the tracer composition whereby when the shell is fired the inertia of the member containing the tracer composition and the cap holder is adapted to overcome the resistance of the fragile device and bring the cap 40 carried by the cap holder against the firing pin and cause the same to explode and the fire to pass through the aperture into the chamber containing the tracer composition

and ignite the same, blowing out from the rear of the tracer attachment shell the firing 45 pin and the cap holder and permitting the products of combustion from the burning of the tracer composition to pass from said chamber out the rear of the shell, substantially as set forth.

50 3. A tracer for projectiles comprising a casing adapted to be fixed in the rear end of the projectile and formed with a central bore closed at its inner end, a sliding member containing the tracer composition mounted 55 in said bore, a cap holder separably secured to said sliding member, a block carrying a firing pin positioned in line with the cap of the cap holder, and a fragile retaining device interposed between said cap holder and 60 said firing pin block, substantially as set forth.

4. A tracer for projectiles comprising a casing, a tube for containing the tracer composition mounted to slide therein, a cap 65 holder mounted to move with said tube, a fixed plug with a central firing pin in line with the cap holder and a fragile retaining device interposed between said cap holder and said firing pin, substantially as set 70 forth.

5. A tracer for projectiles comprising a casing, a movable member containing the tracer composition mounted therein, a cap holder, and a plug formed with a central 75 firing pin and held in position by pressure from the gun, substantially as set forth.

In witness whereof, I have hereunto set my hand and seal at Washington, District of Columbia, this 11th day of April, A. D. 1918, nineteen hundred and eighteen.

ROY LEIGHTON LOWMAN. [L. S.]
